UNITED STATES PATENT OFFICE.

IRA M. DOWNEY, OF WABASH, INDIANA.

MEANS FOR MAKING AND FORMING PRINTING-SLUGS.

1,116,396.

Specification of Letters Patent. Patented Nov. 10, 1914.

Application filed March 15, 1913. Serial No. 754,415.

To all whom it may concern:

Be it known that I, IRA M. DOWNEY, a citizen of the United States of America, residing at Wabash, in the county of Wabash 5 and State of Indiana, have invented new and useful Improvements in Means for Making and Forming Printing-Slugs, of which the following is a specification.

This invention relates to improvements in 10 molds for making printing slugs and has particular application to a mold for making linotype slugs.

In carrying out the present invention, it 15 is my purpose to provide a mold of the class described whereby the slug will be formed with an offset or lateral extension designed to receive the characters or have the same impressed thereon for the purposes of folio or page numbering of books and the like, 20 numbering the lines of bills, briefs, etc., when each line is numbered, and for setting galley numbers and the like.

It is also my purpose to provide a mold 25 by means of which a slug having an offset or lateral extension thereon may be formed and which will be constructed in such manner as to enable the application of the characters from the matrices to the offset or extension, such offset or extension in conjunction 30 with the main body or line of the slug forming, in some instances, a substantially L-shaped slug or line.

With the above and other objects in view, 35 the invention consists in the construction, combination and arrangement of parts hereinafter set forth in and falling within the scope of the claim.

In the accompanying drawings: Figure 1 40 is a perspective view of a printing slug formed from a mold constructed in accordance with the present invention. Fig. 2 is a transverse sectional view through the body of said slug. Fig. 3 is a perspective view of a mold for forming my slug. Fig. 4 is a 45 cross sectional view of the mold. Fig. 5 is a perspective view of the auxiliary or supplemental mold cap, the same being removed or detached from the mold. Fig. 6 is a bottom plan view of a modified form of auxiliary or supplemental mold cap. Fig. 7 is 50 a plan view of a further modification of

auxiliary or supplemental mold cap. Fig. 8 is a still further modified form of auxiliary mold cap. Fig. 9 is still another modification of the mold.

Among the many possible uses or applications of my slug are folio or page numbering for books and the like, line numbering for bills, briefs and the like when each line is numbered and the setting of galley numbers, etc. When using the slug for folio or page and galley numbers and such like, the characters or figures are printed on the same line with the caption or heading. Likewise, the slug prints in alignment with the numbered line in briefs, bills and the like.

In carrying my invention into practice to accomplish the above and other results, I employ a slug having its edges blank and provided with an offset or lateral extension, 70 or a plurality of such offsets or extensions as the case may be, which is designed to receive the characters for printing purposes in the use of the slug. This slug is preferably arranged above the line to be numbered 75 and the extension or offset thereon depends downwardly and aligns with the line to be numbered. Thus, a slug bearing the numbers is independent of the linotypes. In the printing of captions or headings, such 80 captions may be duplicated from page to page without resetting, and the folio or page numbers changed from even to odd and vice versa without affecting the caption or heading. Similarly, when numbering the 85 lines of bills and briefs, the slugs bearing the numbers may be utilized or transferred from one page to another and without the necessity of renumbering the lines, incident to the taking down of the printed line of 90 linotype. Furthermore, the character bearing slugs can be saved from "job to job" thereby eliminating the necessity of resetting frequently used characters.

Referring now to the accompanying 95 drawing in detail, and particularly to Figs. 1 and 2, A indicates the body of the slug formed from a mold constructed in accordance with my present invention, while a denotes the lateral extension or offset formed 100 on the slug. The edges of the body A of the slug are blank while the adjacent end

of the extension or offset, that is the end in proximity to what would be the linotype surface of the body of the slug, is adapted to have characters impressed thereon, as at 5 c. In the present instance, this slug is shown as having only one extension or offset which is located at one end of the slug body and in this connection it will be understood that as many of such extensions or offsets as are 10 desired may be formed on the body of the slug and located or arranged in any convenient relative positions. In the use of the slug, the main body thereof is positioned intermediate the linotypes and preferably 15 above the line to be numbered, while the extension or offset extends downwardly and alines with the line to be numbered, such extension being positioned at either end of the respective line.

20. In Figs. 3 to 8 inclusive, I have shown one form of mold for manufacturing or forming a slug and in the present instance, this mold embraces a body or keeper 1 provided with a suitable number of bolt holes 25 designed to receive bolts or the like whereby the mold may be applied and fastened to the usual mold wheel, and having a flat upper surface; and a cap 2 adapted to rest upon the flat surface of the body or keeper 30 and having a flat surface coöperating with the similar surface of the body or keeper and forming therewith the slot or mold proper, the cap 2 being held spaced apart from the body or keeper 1 by means of 35 liners or spacing blocks 3, 3 at the opposite ends of the cap, such blocks being formed integral with the cap or detachably associated with the mold as a whole, as desired. These spacing blocks or liners are, in this 40 form of my invention separable from the cap 2, and interposed between the mold or slot forming surfaces of the body or keeper and the cap and preferably resting at its ends upon the spacing blocks or liners, is 45 an auxiliary or supplemental mold cap 4 held spaced apart from the flat surface of the body 1. This auxiliary mold cap, is, in this instance, formed with a slot 5 adjacent to one end thereof. Thus, the metal 50 forced into the slot or mold proper from the melting pot will be forced into the slot 5 in the auxiliary or supplemental mold cap with the effect to form an offset or lateral extension on the body of the slug and this 55 offset or extension is designed to have the characters impressed thereon from the line of matrices in proximity to the mold slot, while the main body portion of the slug remains blank. In order to dispose the 60 slot 5 of the auxiliary mold cap inclosing the metal of the extension in alinement with the matrices bearing the characters and to hold the main body portion of the slug away from the character bearing portion of the 65 matrices, I form in the body or keeper 1

of the mold an alining slot 6 which is relatively high as compared with the usual location of the alining slot in the molds now in general use. The height of this slot from normal position is preferably equal to the 70 thickness of the body of the slug bearing the characters, approximately five or six points, (printer's measure).

To trim the character bearing slugs, the trimming knife usually employed and arranged adjacent to the mold wheel is provided with notches to permit the free passage of the extensions on the slug.

In the modified form of auxiliary or supplemental mold cap shown in Fig. 6, 80 the mold slot forming surface of the cap is provided with transverse ribs 7 spaced appropriate distances apart to produce ribbed slugs. In the form of auxiliary mold cap shown in Fig. 7, the same is shown as provided or formed with two slots 5, 5 spaced apart and designed to form two extensions or lateral offsets on the body of the slug, while in the form of auxiliary cap shown in Fig. 8, the extension forming slot is shown 90 formed adjacent the end of the cap opposite from the location of the slot in the cap illustrated in Figs. 3 to 7 inclusive.

Referring now to the form of mold illustrated in Fig. 9, I dispense with the auxiliary or supplemental mold cap and form in the mold or slot forming surface of the main mold cap contiguous the mold slot, a slot or groove 8. This form of mold is particularly adapted for use where it is desired to form the body of the character bearing slug relatively large or deep, thereby eliminating the necessity of increasing the size of the mold which in some instances might result from the use of the auxiliary mold cap.

From the foregoing description taken in connection with the accompanying drawings, the construction and manner of employing my invention will be readily apparent, and while I have herein shown and described one preferred embodiment of my improved printing slug and certain preferred forms of mold for forming or making such slug, I wish it to be understood that I do not confine myself to the details of construction herein described and delineated, as modification and variation may be made within the scope of the claim and without departing from the spirit of the invention. For instance, the keeper or mold body may be provided with any suitable fastening means for securing the same to the mold wheel, and likewise, the mold cap, spacing blocks and keeper or body may be held assembled by any suitable means or in any preferred manner. Similarly, the grooves or slots in the mold cap proper and in the auxiliary mold cap may be formed at any point in the length of the 125 130

respective cap and, when a plurality of such slots or grooves are utilized, the same may have various relative positions.

I claim:

- 5 In a linotype mold, a body or keeper, a mold cap, and an auxiliary mold cap interposed between the confronting faces of said keeper and first-mentioned cap and forming with the adjacent surface of the keeper
- 10 the mold slot and having formed therein a plurality of slots each of a thickness cor-

responding with that of the auxiliary mold cap whereby the molded linotype slug will have lateral extensions thereon adapted to receive characters.

15

In testimony whereof I affix my signature in presence of two witnesses.

IRA M. DOWNEY.
